FILLING STOP MOTION FOR LOOMS

Application filed August 6, 1928. Serial No. 297,856.

This invention relates to a filling stop motion for looms and it is the general object of the invention to provide a mechanism of this type with at least one fork effective to tension the filling so that the latter will cooperate properly with the remaining forks which operate in a manner usual in filling stop motions.

For one reason or another it will occasionally happen that the thread which extends from the selvage to a boxed shuttle will be slack to such an extent that insufficient motion will be given the filling fork to move the same out of operative relationship with the regularly moving actuator. The result is that the loom will stop as though the filling were broken, whereas the defect will not be in the continuity of the filling but in some other part of the loom. For instance, if a shuttle rebounds considerably after being boxed the filling will be slackened to an objectionable extent. Furthermore, if a wide loom is employed for weaving a comparatively narrow fabric the length of filling extending from the selvage over to a box may be of such length as not properly to cooperate with the usual form of filling fork. Also, in automatic weft replenishing looms the shuttle is not completely threaded on the first pick after transfer and where the tension of the filling is increased upon a complete threading of the shuttle it is found that the filling is slack on said first pick after transfer.

It is an important object of my present invention to provide a filling stop motion preferably of the side type which shall have a plurality of tines movable forwardly with the filling fork slide and preferably movable about the same axis, at least one of the tines being positioned to extend below the race plate and behind the reed so as to tension the filling in whatever position it may assume by moving a portion of the same behind the grid which cooperates with the remaining tines to tip the latter out of stopping position.

It is a more specific object of my present invention to locate the tensioning and detecting tines in such relation that the detecting tines which operate to stop the loom will be located between the tensioning tine and the

adjacent selvage, the purpose of this relation being to secure more uniform tension on that part of the filling which engages the detecting tines. I do not wish to be limited to this relation but I have found it to be desirable.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a top plan view of a portion of a loom having my invention applied thereto showing the lay in extreme forward position and the shuttle in such a position as it might assume after rebounding,

Fig. 2 is a vertical section on line 2—2 of Fig. 1 on an enlarged scale showing the tensioning tine extending behind the reed line and indicating the detecting tines as being in non-stopping position,

Fig. 3 is a horizontal section on line 3—3 of Fig. 2, and

Fig. 4 is a detailed vertical section on line 4—4 of Fig. 2.

Referring to the drawings, I have shown a loom frame 10 on which is mounted the base 11 of the side stop motion. Upstanding from said base are two parallel spaced walls 12 between which is moved the slide 13. The latter has a forward extension 14 operatively connected to the left hand end of a knock-off lever 15 as shown in Fig. 1. Said lever is pivoted as at 16 to the shipper handle stand 17 of the loom frame and has an arm 18 extending to the right of the pivot 16 and lying in front of the shipper handle 19.

The lay 20 is driven by appropriate mechanism to move back and forth in the loom to approach and recede from the plate 11. The lay is provided with a reed 21 of the usual kind and also a box back 22. The latter positions the shuttle S and the forward surface 23 of the box back is in substantial alignment with the front edge of the reed 21 as shown more particularly in Fig. 3. A grid 24 having a plurality of spaced wires 25 is secured to the lay and has the upright

portions of the wires set preferably slightly behind the reed line. The upper end of said wires may be upwardly and rearwardly inclined as at 26 if desired and be connected together as suggested in Fig. 1.

An actuator head 30 having a forwardly extending hook end 31 moves in a slot 32 formed in the slide 13. Said actuator head is moved forwardly by mechanism not shown but well understood every second pick of the loom when the active shuttle is on that side of the lay adjacent the plate 11.

Under normal conditions the parts are in the position shown in Fig. 1 with the shipper handle 19 in the running position indicated and with the slide 13 in rearward position. When weft W extends from the shuttle to the selvage V of the cloth C it will pass in front of the wires 25. The latter are secured to the lay by passing into the latter in the bottom of a well 33 which extends across the lay below the surface R along which the shuttle S moves. When the weft W is broken, however, mechanism to be described hereinafter operatively connects the head 30 and slide 13 to move the latter forwardly and cause rocking of the lever 15 to unseat the shipper handle 19, whereupon the loom will be stopped.

30 The matter thus far described is of common construction in so-called side filling stop motions and forms no part of my present invention.

In carrying my invention into effect I provide an improved means for establishing connection between the hook 31 and the slide 13 said means including detecting and tension tines. Accordingly, I provide the rear end of the slide 13 with a pivot pin 40 extending across the slot 32 and on which are pivotally mounted a detecting element 41 and a tensioning element 42 located to the right of the detecting element as viewed in Fig. 1.

The detecting element includes a holding member 43 having a forwardly extending loop 44 which is adapted for cooperation with the hook 31 when weft is absent. The head 43 also has depending therefrom in this instance a pair of detecting tines 45 which pass between corresponding wires 25 of the grid. The bottoms of said tines 45 extend into the well 33 to a position below the surface R along which the shuttle moves.

The tensioning element 42 as shown herein comprises a single depending tine 50 the lower end of which also extends into the well 33 and below the surface R. As shown clearly in Fig. 2 tine 50 extends behind the detecting tines 45 and said tensioning tine 50 may have a forwardly extending arm 51 which by means of a tension spring 52 attached to an adjustable hook 53 carried by the slide 13 acts to hold the tensioning tine in a substantially vertical position such as shown in Fig. 2. As shown in Fig. 1 the

arm 51 may extend across a portion of the slide 13 and be positioned by the latter under tension of the spring 52.

The adjustable hook 53 may be formed substantially as shown in Fig. 1 and held in adjustable position for both angular and longitudinal adjustment relatively to the slide 13 by screw 54.

In operation, the weight of the hook engaging loop 44 will hold the detecting tines 45 in a substantially vertical direction and the spring 52 will act to hold the tensioning tine 50 also substantially vertical, but located behind the detecting tines and positioned to enter the space between two of the grid wires 25. As the lay moves forwardly with the weft present and with the shuttle on that side of the loom adjacent the filling stop motion, the tensioning tine 50 will pass between two of the wires 25 and inasmuch as said tine extends below the surface R it will in every instance engage weft when weft is present on detecting beats of the loom. As the lay continues to move forwardly the tine 50 will move the weft W behind the reed line to the position shown in Fig. 3, thus removing any slackness in the weft and moving the latter to a position across the grid where it may properly cooperate with the detecting tines to tilt the latter.

When the lay reaches its extreme forward position the head 30 will move forwardly but without effect unless the detecting tines have been unmoved due to weft absence, in which case the shipper handle 19 will be unseated, as previously described.

The relation between the detecting and tensioning tines is set forth clearly in Fig. 3, where it will be seen that the weft W is moved rearwardly as at W' by the tensioning tine 50 on each detecting beat of the loom.

The detecting tines 45 will be moved to the position shown in Fig. 2 when weft is present so that the loop 44 will be elevated out of the path of the hook 31 and the latter will move forwardly without stopping the loom. Should weft be absent, however, the tensioning member will have no function to perform and the spring 52 will therefore remain at rest relatively to the slide 13 but will move forwardly with the latter when weft is absent.

Should the shuttle be nearer the center of the loom than it should be due to rebounding, slackness will exist in the weft W, but this will ordinarily be less than the amount that can be taken up by the tensioning tine as the latter moves to the position shown in Fig. 3. The spring 52 will yield should the weft W be insufficient to permit the tensioning tine 50 to remain vertical for the complete forward stroke of the lay.

From the foregoing it will be seen that I have provided a simple and effective means for tensioning and also detecting for the presence of weft on detecting beats of the loom.

It will further be seen that the detecting and tensioning elements are mounted on the same pivot pin and can yield forwardly under pressure of the weft as the lay advances. It will 5 also be noted that the tensioning member 50 extends below the level of the lay along which the shuttle moves. Furthermore, the detecting element 41 may be located between the tensioning element 42 and the selvage V of 10 the cloth, a condition which insures uniformity of tension in that portion of the weft which comes in contact with the detecting tines.

Having thus described my invention it will 15 be seen that changes and modifications may be made therein by those skilled in the art without departing from the spirit and scope of the invention and I do not wish to be limited to the details herein disclosed, but what 20 I claim is:

In a filling detecting and tensioning stop motion for a loom, a lay having a surface along which the filling extends, a grid on the lay, a slidably mounted member, means carried thereby defining a pivotal support, a tensioning tine pivotally mounted on the support and positioned to extend behind the grid and below the surface along which the filling extends when the lay is in its forward position, 25 said tensioning tine having a forwardly extending normally horizontal arm, a substantially horizontal tension spring connected to the arm and having the forward end thereof secured to the member to hold said tensioning tine relatively fixed with respect to the member when said tensioning tine engages filling extending across the grid, said tension spring causing the tensioning tine to take up slack in the weft, and a detecting element pivotally mounted on the support to be tilted by filling extending across the grid.

In testimony whereof I have hereunto affixed my signature.

JESSE W. SIMPSON.
